THERMAL RETARDER

Clark M. Osterheld, Stoughton, Wis., assignor to
McGraw Electric Company, Elgin, Ill., a corporation of Delaware

Application August 24, 1946, Serial No. 692,899

8 Claims. (Cl. 219—39)

1

My invention relates to thermal retarders and more particularly to water heater control systems comprising a specific form of thermal retarder.

One object of my invention is to provide a water heater control system that shall cause immediate energization of an electric heater for a hot water tank after closure of a time-controlled off-peak switch, in case the tank is full of cold water.

Another object of my invention is to provide a water heater control system that shall cause energization with a predetermined time delay period after closure of a time-controlled off-peak switch, of an electric heater in case only a relatively small amount of cold water is in the tank, said time delay being caused by a specific form of thermal retarder.

Other objects of my invention will either appear from a description of one form of thermal retarder embodying my invention or will be set forth during the course of such description and particularly in the appended claims.

In the drawings, the single figure is a view in vertical longitudinal section, of a standard domestic hot water tank having operatively associated therewith a thermal retarder embodying my invention.

A hot water tank 11 comprises a lower closure member 13 having a cold water inlet pipe 15 secured thereto and an upper closure member 16 having a hot water outlet pipe 17 secured thereto. A mass 19 of heat-insulating material such as mineral wool, surrounds tank 11 and is held in proper operative position by an outer casing 21. A preferably single electric heater 23 is located near the lower end of tank 11 and may be housed in a tunnel member 25. All of the details thus far described are already old and well-known in the art.

The control system embodying my invention includes a lower thermally-actuable switch comprising a bimetal bar 27 which is adapted to be positioned on a fixed contact member 29 while its upper free end is adapted to be engaged with and be disengaged from a second fixed contact member 31. The location of the bimetal bar 27 is such that substantially all of the water in the tank will be heated to a relatively high temperature before contact between bar 27 and contact member 31 will be broken while the engagement will be effected when thermostatic bar 27 is subject to cold water. By cold water I mean water the temperature of which may vary between say 70° F. and 130° F. while by hot water I mean water the temperature of which is on the order

2

of 150° F. I do not desire to be limited to the use of a bimetal bar since any other thermally-actuable element effective for the same purpose may be used.

5 I provide a second bimetal bar 33 which is adapted to have its lower end fixed on a contact 35 while its upper free end is adapted to engage with and be disengaged from a second fixed contact 37. The thermally-actuable switch comprising the bimetal bar 33 is adapted to be positioned in heat-receiving engagement on tank 11 at preferably about one-half of the total height of the tank.

A thermal retarder designated generally by the 15 numeral 39 comprises a two-part tube, the lower substantially vertically extending part 41 being adapted to be filled with a fluid 43 such as water. The upper closed tube 45 is adapted to be connected by a relatively small bore 47 to tube 41 and the upper tube 45 is adapted to extend at an angle relatively to the horizontal. The lower tube 41 is closed by a closure member 49 which may either be screwed in place on the lower open end of tube 41 or may be welded or soldered or 20 brazed thereto.

I provide a relatively low wattage heating coil 51 which is insulatedly mounted on tube 41.

I provide further a bimetal bar 53, the lower end portion of which is insulatedly supported on 25 the lower end portion of tube 41 as by a block 55 of electric- and heat-conducting material. The upper freely movable end of bimetal bar 53 is adapted to engage with and be disengaged from a fixed contact member 57 which is also insulatedly supported on tube 41. I may here say that the material of which the tubes 41, 45 and 35 57 are made may be metal such as brass or aluminum.

I provide a time-controlled switch for controlling the heater 23, comprising a contact arm 59 adapted to be engaged with and disengaged from a second contact arm 61 by a continuously operating timing means. I have not shown a timer in detail since these are already old and well-known 40 in the art and it is only necessary that the timing means be able to cause engagement of the contact arms 59 and 61 during one or more off-peak periods of a 24-hour day, say from 10:00 p. m. or 11:00 p. m. to 6:00 a. m.

50 A supply circuit conductor 63 is connected to contact arm 59 while contact arm 61 is connected with contact block 37 as by a conductor 65. Contact 35 is connected by a conductor 67 to one terminal of the heater 23 as well as to 55 contact 55 by a conductor 69. Contact 57 is con-

nected by a conductor 71 with conductor 65 and therefore directly with contact arm 61.

One terminal of heating coil 51 is adapted to be connected with contact 57 while the other terminal of heating coil 51 is adapted to be connected to a movable contact 73 of an adjustable rheostat 75. The other terminal of rheostat 75 is connected by a conductor 77 to the other terminal of heater 23 as well as to contact 29. Contact 31 is connected by a conductor 79 with the second supply circuit conductor 81.

I wish to here point out that the amount of electrical energy translated into heat in the electric heating coil 51 is relatively small, that is it may be on the order of 5 to 10 watts, it being obvious that the fluid 43 in tube 41 will be caused to vaporize sooner when the energy is 10 watts than when it is 5 watts. Vaporization of the fluid 43 results in a decided temperature rise of the metallic tube 41 with the result that bimetal bar 53 will be disengaged from contact member 57 with which it is in engagement while the temperature of the fluid is relatively low.

Let it be assumed that the tank has just been filled with cold water and therefore contact bars 27 and 33 will be in engagement with the respective contact members 31 and 37. Then assume an engagement of contact arms 59 and 61 of the time-controlled clock is effective, an energizing circuit through the electric heater 23 will be closed traceable as follows: from supply circuit conductor 63, through the engaged contact arms 59 and 61, conductor 65, through closed contact bar 33, through conductor 67, heater 23, through bimetal bar 27 and from there through conductor 79 to the other supply circuit conductor 81.

This will result in heating of water in the tank and particularly of the water in the upper part of the tank, the top of the cold water falling gradually until finally the water affecting the upper bimetal bar 33 will be hot enough to cause it to move the bar into the position shown in the drawing which will deenergize the electric heater 23.

At the same time an energizing circuit was closed through heating coil 51 traceable as follows: from supply circuit conductor 63, through engaged contact arms 59 and 61 of the time-controlled switch, conductor 71, through heating coil 51, through that part of the adjustable rheostat 75 in circuit, through conductor 77, through bimetal bar 27 and from there through conductor 79 to the other supply circuit conductor 81. The length of time which it will require to vaporize the water or at least part of it in tube 41, is on the order of 3 to 5 hours depending entirely upon the conditions and the wishes of the user of the system embodying my improved thermal retarder. When the temperature of bimetal bar 53 has been raised to a predetermined high value it will move into engagement with contact 57.

A second energizing circuit is closed through the electric heater 23 traceable as follows: from supply circuit conductor 63, through the engaged contact arms 59 and 61, conductor 71, bimetal bar 53, conductor 69, electric heater 23, through bimetal bar 27 and conductor 79 to the second supply circuit conductor 81. This will cause heating of the rest of the water in the tank assuming, of course, that no further call for hot water is made on the tank until substantially all of the water in the tank 11 has been heated to a temperature on the order of 150° F. when bimetal bar 27 will be moved out of engagement with contact member 31 whereby the last mentioned energizing

circuit is interrupted. This will also interrupt the energizing circuit through heating coil 51 so that ultimately the bimetal bar 53 will flex away from engagement with contact 57 starting the day or at the end of an off-peak period which may be said to extend from 10:00 or 11:00 p. m. to say 6:00 a. m. in the morning, with a tank full of hot water ready for the daily demands for hot water.

Various modifications may be made in the device embodying my invention without departing from the spirit or scope thereof and all such modifications clearly coming within the scope of the appended claims shall be considered as part of my invention.

15 I claim as my invention:

1. A water heater control system for a hot water tank comprising an electric heater, a first thermally-actuable switch adapted to be subject to tank water temperature near the lower 20 end of a tank and adapted to be closed when subject to cold water and to be open when subject to hot water in a tank, a second thermally-actuable switch adapted to be subject to tank water temperature intermediate the ends of a tank and adapted to be in closed position when subject to cold water and to be in open position when subject to hot water in a tank, a thermal retarder switch subject to tank water temperature intermediate the ends of a tank and comprising 25 a first fluid container, a second container connected with said first container by a small bore, a fluid in said first container, a low wattage heating coil around said first container, a bimetal bar subject to heat from said first container and a timer controlled switch connected in series circuit with said first and said second thermally-actuable switches and said electric heater, said first and second switches being adapted to effect immediate energization of said electric heater 30 35 upon closure of said timer controlled switch, when both said switches are subject to cold water.

2. A water heater control system for a hot water tank comprising an electric heater, a first thermally-actuable switch adapted to be subject to tank water temperature near the lower 40 end of a tank and adapted to be closed when subject to cold water and to be open when subject to hot water in a tank, a second thermally-actuable switch adapted to be subject to tank water temperature intermediate the ends of a tank and adapted to be in closed position when subject to cold water and to be in open position when subject to hot water in a tank, a thermal retarder switch subject to tank water temperature intermediate the ends of a tank and comprising 45 50 a first fluid container, a second container connected with said first container by a small bore, a fluid in said first container, a low wattage heating coil around said first container, a bimetal bar subject to heat from said first container and a timer controlled switch connected in series circuit with said first and said second thermally-actuable switches and said electric heater, said first switch and said thermal retarder switch being adapted to jointly effect energization of said electric heater with a predetermined time period of delay after closure of said timer controlled switch when said first thermally-actuable switch alone is subject to cold water.

3. A water heater control system as set forth in claim 2 and comprising means for varying said predetermined time of delay.

76 4. A water heater control system as set forth in

claim 2 and comprising manually-actuable means for varying said predetermined time of delay.

5. A water heater control system as set forth in claim 2 and comprising a manually-actuable rheostat connected in series circuit with said heating coil for varying said predetermined time of delay.

6. A water heater control system for a hot water tank comprising an electric heater, a first thermally-actuable switch adapted to be subject to tank water temperature near the lower end of a tank and adapted to be closed when subject to cold water and to be open when subject to hot water in a tank, a second thermally-actuable switch adapted to be subject to tank water temperature intermediate the ends of a tank and adapted to be in closed position when subject to cold water and to be in open position when subject to hot water in a tank, a thermal retarder switch subject to tank water temperature intermediate the ends of a tank and comprising a first fluid container, a second container connected with said first container by a small bore, a fluid in said first container, a low wattage heating coil around said first container, a bimetal bar subject to heat from said first container and a timer controlled switch connected in series circuit with said first and said second thermally-actuable switches and said electric heater, said first switch and said thermal retarder switch being adapted to jointly effect energization of said electric heater with a predetermined time period of delay after closure of said timer controlled switch when said first thermally-actuable switch alone is subject to cold water, said first thermally-actuable switch being effective to de-energize said electric heater when substantially all of the water in the tank is hot.

7. In a water heating and control system, the combination with a water tank, a heater therefor, and a thermostat responsive to the temperature of the water in said tank, of, a thermal re-

5 tarder comprising a container having a small port removed from the bottom thereof, a heater for said container for heating and vaporizing a fluid therein, said heater being controlled by said thermostat, a second container having a port removed from the top thereof for alternately receiving fluid from the first container and returning it thereto, said containers being otherwise closed, a vaporizable fluid in said containers, and 10 control means comprising a thermostat responsive to the temperature of said first container for controlling said heater for said tank.

15 8. The combination with apparatus to be controlled, and a control device therefor, of, a thermal delay relay therebetween comprising two containers consisting of a vaporizer and a receiver thereabove, said containers being closed for confining vapor and liquid therein, having a passage from the upper portion of the vaporizer to 20 the lower portion of the receiver, and characterized by the lack of any other passage between said containers which, with said first passage, would permit a continuous circulation of fluid through such passages and between said two containers 25 in response to heating of said vaporizer, a vaporizable fluid in said containers, a heater for said vaporizer controlled by said control device, and a thermostat responsive to the temperature of said vaporizer for controlling said apparatus to be 30 controlled.
